UNITED STATES PATENT OFFICE.

HENRY G. VOIGHT AND NORMAN B. HURD, OF NEW BRITAIN, CONNECTICUT,
ASSIGNORS TO THE RUSSELL & ERWIN MANUFACTURING COMPANY, OF
NEW BRITAIN, CONNECTICUT.

DOOR-CHECK.

SPECIFICATION forming part of Letters Patent No. 685,804, dated November 5, 1901.

Application filed February 6, 1899. Serial No. 704,620. (No model.)

To all whom it may concern:

Be it known that we, HENRY G. VOIGHT and NORMAN B. HURD, citizens of the United States, residing in New Britain, in the county 5 of Hartford and State of Connecticut, have invented certain new and useful Improvements in Door-Checks, of which the following is a specification.

Our invention relates to improvements in 10 door-checks; and the main object of our invention is to provide a check especially adapted for checking a door that swings both ways.

In the accompanying drawings, Figure 1 is a front elevation of our door-check, the guide- 15 plate being shown in vertical section. Fig. 2 is a plan view of the same. Fig. 3 is a vertical section of a portion of the same on the line $x-x$ of Fig. 2, the crank-shaft, crank-arm, and crank-pin being shown in elevation. 20 Fig. 4 is a reverse plan view of our check with the cap of the crank-chamber removed. Fig. 5 is a like view of the same with the piston-slide drawn partly back and the crank-shaft moved one-quarter of a revolution.

25 A designates the cylinder, and B the body of the case, provided with a bracket-plate 6 for securing the said case to a door. Within the said case is a crank-shaft 7, carrying a crank-arm 8 and crank-pin 9, either with or 30 without a friction-roller. Within the cylinder is an ordinary piston (not shown) and piston-rod 10, which may be connected by any suitable means to the piston-slide 11. The generic features of a door-check with a piston-slide having an oblique slot and a crank with its pin in said slot for reciprocating the slide and piston are made the subject of a companion application, Serial No. 704,474, filed February 4, 1899, Patent No. 632,291, dated 35 40 September 5, 1899, and therefore this application, in so far as the crank and slide are concerned, is confined to a slide having the two inclined slots. The said piston-slide is provided with two oblique slots 19, that slant 45 from the axial line of the piston-rod outwardly in opposite directions, the two slots together forming a V-shaped slot with the outer or rear-most point of the V rounded off, as shown in Figs. 4 and 5, on a curve whose center is substantially the inner point of the V, so that

said slot may be substantially filled at all points by the diameter of the crank-pin 9. The under side of the piston-slide and crank-arm are covered by the cap or under plate 12, Fig. 3.

55 For what we may call a "universal connection" for double-acting doors we prefer the connecting or operating mechanism shown in Figs. 1 and 2, which may be applied either to doors with one broad side flush with the 60 face of the casings or to doors which are set in more or less relatively to the face of the casings. In this illustration the crank-lever 13 is offset at 14 to bring its outer end to one side of the axis of the cylinder, and said outer 65 end is provided with a headed pin or roller 15. The guide-plate 16 is slotted longitudinally, as shown at 17, the width of the slot being fitted to the body of the headed pin or roller. The slot 17 at one end is enlarged, 70 as at 18, sufficiently to let the head of the headed pin or roller pass endwise through it. The guide-plate is provided with ordinary screw-holes, whereby said plate may be secured to the woodwork immediately over the 75 top edge of the door, and thus bring the crank-lever into the proper position to force the piston home when the case B is attached to the door in the relative position to the guide-plate shown in Figs. 1 and 2. Figs. 3 and 4 80 show the parts in the same position, it being understood that the door is closed. With this connection thus applied it is wholly immaterial whether the face of the casings be flush with one side of the door or not. While 85 we prefer the connection illustrated in Figs. 1 and 2, it is evident that any other connections that will give the crank-shaft a like movement may be substituted therefor without changing the operation of the crank-shaft 90 and the piston-slide.

95 Our check is designed for use with any ordinary double-swinging doors, which may be closed by any suitable springs or force applied in any ordinary manner, and consequently no spring is necessary for the crank-shaft.

The check is designed to have its crank-pin at the apex of the V or double-inclined slot when the door is closed, as shown in Figs. 3 100

and 4. Upon opening the door the crank-pin is forced up one or the other of the slots 19, thereby forcing the piston-slide and piston back from the position shown in Fig. 4 to that shown in Fig. 5 when the crank-shaft has been moved one-quarter of a revolution. In said Fig. 5 we have shown the crank-pin as having moved along the upper one of the slots 19; but the movement of the piston-slide and attached piston is precisely the same no matter which way the door opens or which slot the pin travels in. If the door is opened more than enough to give a quarter-turn to the crank-shaft, the slide moves back continuously until its right-hand end reaches the point indicated by the broken-line contour in Fig. 5, the pin then being near the middle of the length of the slot, where it travels a short distance without imparting any movement to the slide; but if motion to the crank is continued far enough to give a half-revolution to the crank it is brought into the apex of the V-shaped slot and the slide is moved forward—that is, to the left—and carried nearly, but not quite, to the position illustrated in Fig. 5 for the quarter-turn. The closing movement of the door when released to the force of its spring or springs moves the crank in the reverse direction and forces the piston into the cylinder to check the door.

The extreme limit of the backward movement of the slide upon a half-revolution of the crank-shaft from the position shown in Fig. 4 is indicated at the right-hand end of Fig. 5 by the broken-line contour. The position of the slide at a quarter-revolution of the crank-shaft from the position shown in Fig. 4 is shown by full lines in Fig. 5.

We are aware that a prior patent shows and describes a liquid door-check for a door that swings either to the right or to the left, although swinging one way only, the said check having a single crank-arm with its pin in a doubly-inclined slot of a slide that moves at right angles to the movement of the piston, the angle of inclination of said slot being much nearer a right angle to the movement of this slide than it is to forty-five degrees thereto, and we hereby disclaim the same.

By means of the crank-pin and piston-slide in our check having the doubly-inclined slot at about forty-five degrees to the axis of the piston the movement of the piston-slide is substantially uniform for a given movement of the crank-shaft during its first quarter-revolution in opening the door. In other

words, the piston has its fastest movement relatively to the crank-shaft on the last quarter of a revolution of said shaft in closing the door, a very important matter in a pneumatic check, whereas the reverse is true in a door-check having a slot extending at right angles to the slide, or much more nearly to a right angle, as in the door-check hereinbefore disclaimed.

It is apparent that some changes from the specific construction herein disclosed may be made, and therefore we do not wish to be understood as limiting ourselves to the precise form of construction shown and described, but desire the liberty to make such changes in working out our invention as may fairly come within the spirit and scope of the same.

We claim as our invention—

1. The combination of a door-check case having a cylinder with the crank-shaft mounted in said case at a right angle to the length of said cylinder, a crank-arm and crank-pin on the said shaft, a piston moving longitudinally within said cylinder, the piston-slide rigidly connected with the said piston and having the two oppositely-inclined slots within which the said crank-pin is arranged, the said two slots extending at about forty-five degrees to the axial line of the piston and meeting each other in a right angle, and mechanism for connecting the said crank-shaft and door-check case with a frame and a door that swings both to the right and to the left, substantially as described.

2. The combination of a door-check case, having a cylinder made rigid with the said case, with the piston-slide mounted within guides in the said case to slide in the longitudinal direction of the said cylinder and having the two oppositely inclined and connected slots arranged at substantially a right angle to each other and extending at about an angle of forty-five degrees to the axial line of the said cylinder, the piston within said cylinder rigidly connected with the said piston-slide for moving simultaneously therewith in the same direction, the crank-shaft arranged at right angles to the said cylinder and having a crank-pin working within the said slots and mechanism for connecting the said crank-shaft and door-check case with a frame and a door that swings both ways, substantially as described.
